(No Model.)

L. McCARTHY.
INSULATED RAIL CHAIR.

No. 513,950.

Patented Jan. 30, 1894.

UNITED STATES PATENT OFFICE.

LOUIS McCARTHY, OF BOSTON, MASSACHUSETTS.

INSULATED RAIL-CHAIR.

SPECIFICATION forming part of Letters Patent No. 513,950, dated January 30, 1894.

Application filed September 27, 1892. Serial No. 447,004. (No model.)

To all whom it may concern:

Be it known that I, LOUIS McCARTHY, a citizen of the United States, residing at Boston, in the county of Suffolk and State of Massachusetts, have invented certain new and useful Improvements in Insulated Rail-Chairs, of which the following is a specification, reference being had therein to the accompanying drawings.

10 My invention has for its object to provide an insulated rail-chair for railways which shall be strong and durable and which shall effectively insulate the rails and it consists in a rail-chair constructed as hereinafter set forth and the novel features of which are pointed out in the claims which are appended hereto and made a part hereof.

I have shown my invention in the best form now known to me in the accompanying drawings, in which—

15 Figure 1 is a perspective showing my improved chair with a portion of the ends of two rails attached thereto. Fig. 2 is a transverse section on line 2—2 Fig. 1.

20 Having reference to the drawings, A is a portion of a sleeper.

B is the bed or base piece of the chair which may rest on the sleeper. The bed B is provided with holes c to receive securing bolts d, 25 these bolt holes being at their upper portions less in diameter than the heads of the bolts, but below the contracted portion being sufficiently enlarged to accommodate the heads of the bolts as also the surrounding mass of insulating material f. The insulating material employed is preferably sheet mica. A layer of this material is placed on top of the bed piece and a top plate of metal g is placed above this insulating layer, said plate serving not only as a rest for the base of the rail, but also to compress and retain the insulating layer. Cheek pieces j of a shape to fit the base and web of the rail D are provided and these are extended laterally to receive securing bolts d. Each of the pieces j is also preferably provided at the edges with a skirt or over-hang k which operates to shed moisture and protect the insulation. The horizontal bolts l are employed which pass through the 50 web of the rail as also through the vertical portions of the cheek pieces and serve to hold the rail securely in place. The edges of the

insulation which is placed between the bed B and top-plate g are protected by a casing m preferably of rubber or similar non-conducting material which may be molded around the chair after it has been put together and prepared for the reception of the rail and cheek pieces.

55 The parts are put together as follows: A series of sheets of mica which have been cut to the proper shape to fit the enlarged portion of the bolt holes in the bed pieces are strung on the bolts d. Another series of sheets of mica of a size to fit the smaller portions of the said bolt holes are also strung on the bolts. A sufficient number of larger sheets of mica to form the required thickness of insulation between the bed B and the plate g and which have been provided with holes for the bolts d are then laid on the bed and upon them is placed the plate g which is also provided with holes for the reception of the bolts d. The bolts and their insulating material having been introduced into the holes c in the bed B, and the stems thereof being passed through the holes in the plate g, the nuts p are then screwed firmly onto the bolts binding the bed and plate firmly together and compacting and compressing the mica insulation. Sheets of mica are placed around the edges of the heads of the bolts. The heads of the bolts are preferably rounded as shown and beneath them is placed a layer of mica of the proper thickness. Concaved plugs q are then driven or shrunk into the lower portions of the bolt holes. The plug q should completely fill the holes to prevent the admission of moisture to the insulation. The casing m is then molded around the sides of the chair and it is ready for use. The rails are placed on the chair and the cheek pieces applied and secured by nuts r on the bolts d and by horizontal bolts l as will be clear from Fig. 2. The chair may be spiked or secured in any well known manner to the sleeper. It will also be obvious that the chair may be used to support the middle portions of the rails as well as the end portions. The length or other dimensions of the chair as also the number of bolts employed is not material. Mica is especially valuable as an insulating material to be used in this device because of its high insulative quality, is not affected by changes of temperature,

and when compacted and compressed is unyielding under pressure or strain and very durable.

What I claim is—

- 5 1. An insulated rail-chair comprising a bed-piece provided with holes for the reception of securing bolts, a top-plate, a layer of insulating material between the bed-piece and the top-plate, cheek-pieces applied to the upper 40 surface of said top-plate, securing bolts fitted to the holes in the bed-piece and holding both the said top-plate and the cheek-pieces in place, and insulating material surrounding the bolts in the holes of the bed-piece.
- 10 2. An insulated rail-chair comprising a bed-piece provided with holes for the reception of securing bolts, a top-plate, a layer of insulating material between the bed-piece and the top-plate, cheek-pieces applied to the upper 45 surface of said top-plate, securing bolts fitted to the holes in the bed-piece and passing through both the top-plate and the cheek-pieces and holding both the said top-plate and the cheek-pieces in place, and insulating 50 material surrounding the bolts in the holes of the bed-piece.
- 15 3. An insulated rail-chair comprising a bed-piece provided with holes for the reception of securing bolts, a top-plate, a layer of insulating material between the bed-piece and the top-plate, securing bolts having their inner 55 ends fixed in the holes in the bed-piece and surrounded by insulating material and having their stems passed through the insulating layer and top-plate, nuts on the said bolts above the top-plate, cheek-pieces through which the stems of the bolts also pass and nuts on the bolts above the cheek-pieces, substantially as described.
- 20 4. An insulated rail-chair comprising a bed-piece, a top plate, an interposed layer of insulating material, suitable securing devices therefor, and a casing of insulating material 60 surrounding the sides, of the bed-piece and the top-plate to protect the insulating material between them substantially as and for the purposes set forth.
- 25 5. An insulated rail-chair comprising a bed-piece, a top plate, an interposed layer of insulating material, suitable securing devices therefor, and a casing of insulating material 65 surrounding the sides, of the bed-piece and the top-plate to protect the insulating material between them substantially as and for the purposes set forth.
- 30 6. The combination with an insulated rail-chair of cheek pieces extended laterally and provided with a skirt or overhang substantially as and for the purposes set forth.
- 35 7. In an insulated rail-chair the combination of the bed piece B, the top plate g, an insulating layer interposed between said top plate and said bed piece, the cheek-pieces securing bolts d set in holes in said bed piece and insulated therefrom and provided with nuts for holding the top-plate and cheek-pieces in place and plugs q for closing said holes, substantially as set forth.

In testimony whereof I affix my signature in presence of two witnesses.

LOUIS McCARTHY.
